BURNER CONTROL SYSTEM

Meade J. Maynard, Minneapolis, Minn., assignor
to Minneapolis-Honeywell Regulator Company,
Minneapolis, Minn., a corporation of Delaware

Application January 21, 1938, Serial No. 186,123

8 Claims. (Cl. 158—28)

This invention relates to a burner control system and more particularly to one employing means for checking the ignition.

It is quite common with fluid fuel burner control systems, particularly oil burner control systems, to provide an electrical ignition means for igniting the fuel. This means usually takes the form of a high voltage circuit including spaced electrodes between which a spark occurs upon energization of the high voltage circuit. It is highly desirable that the oil burner or other fuel feeding means not be placed into operation until such time as a proper spark occurs across the ignition electrodes. Accordingly, various arrangements have been proposed from time to time to prevent operation of the fuel feeding means until the ignition means is operating properly. One such arrangement is disclosed in the application of Willis H. Gille, Serial No. 39,700, filed September 9, 1935. In the arrangement of this application, means is utilized which is responsive to the high frequency current flow in the ignition circuit adjacent to the spark gap. While the arrangement of the above mentioned Gille application was highly satisfactory as far as operation was concerned, the apparatus employed electronic tubes and other complicated equipment which unduly added to the expense of the control system and necessitated more frequent service costs by reason of the limited life of the electronic tubes employed therein.

An object of the present invention is to provide a spark checking arrangement for a burner control system in which a circuit resonant to the high frequency current accompanying a proper spark is connected in series with the spark gap closely adjacent thereto and in which the flow of fuel to the burner is controlled in accordance with the current flow in said resonant circuit.

A further object of the present invention is to provide such a spark checking arrangement in which the inductance and capacitance elements of the resonant circuit are located in the electrode member itself.

A further object of the present invention is to provide such a spark checking arrangement in which temperature responsive means is employed to actuate a switch in the burner circuit, which temperature responsive means is subjected to the heating effect of the current in the resonant circuit.

Other objects of the invention will be apparent from a consideration of the accompanying specification, claims and drawing, of which:

Figure 1 is a schematic view of a burner control system embodying one species of my invention;

Figure 2 is a detail view in section of one of the electrodes employed in the spark checking arrangement of the invention;

Figure 3 is a schematic view of a portion of an oil burner control system embodying a second species of the invention, and

Figure 4 is a view of the electrode and associated switch of the second species.

Referring to the drawing, more particularly to Figure 1 thereof, an oil burner is generally designated by the reference numeral 10. This oil burner is of conventional construction and comprises a burner motor 11 and a nozzle 12 through which a mixture of fuel and air is forced.

A room thermostat 15 is employed as a primary control of the oil burner. This room thermostat is of conventional construction being shown as comprising a bimetallic element 16 to which is secured a contact arm 17 adapted to engage with a contact 18 upon the temperature falling below a predetermined point.

The thermostat 15 controls the energization of a relay 20. This relay comprises a relay coil 21 and a pair of switch arms 22 and 23 adapted to be moved into engagement with contacts 24 and 25, respectively. Switch arms 22 and 23 are biased out of engagement with contacts 24 and 25 by any suitable means (not shown) and are adapted to be moved into engagement therewith upon energization of relay coil 21.

A thermal safety switch is generally designated by the reference character 27. This switch may be of any suitable form, one preferred form being that shown in the patent to Frederick S. Denison No. 1,958,081, issued May 8, 1934. As shown in the drawing, this switch comprises a pair of switch blades 28 and 29 the lower one 29 of which is pivotally mounted so that unless restrained it will drop away from switch blade 28. Normally projecting under the lower end of switch blade 28 to hold it in engagement with switch blade 28 is a bimetallic element 30. This bimetallic element 30 has associated therewith a heater 31 which upon energization thereof is adapted to heat the bimetallic element 30 and warp it to the right. If this heating continues sufficiently far, the bimetallic element 30 will move from under the end of switch blade 28 allowing the latter member to drop away from switch blade 28.

A stack switch is generally indicated by the reference numeral 35. This switch is shown in

a purely schematic form in the drawing. As shown, the switch comprises two switch blades 36 and 37. Switch blade 36 is movable between contacts 38 and 39 and switch blade 37 is movable between contacts 40 and 41. The switch blades 36 and 37 are adapted to be actuated by a temperature responsive element (not shown), which element is placed so as to be responsive to stack temperature. The switch blades 36 and 37 are connected to the temperature responsive element by a slip friction connection allowing the blades 36 and 37 to be moved from one contact position to their other contact position upon an initial temperature change in either direction, after which the temperature responsive element continues to move without movement of the switch blades by reason of the slip friction connection. This construction is well known in the art and is for the purpose of quickly responding to a change in direction of a temperature change. The assembly consisting of the switch blade 36 and the contacts 38 and 39 is so designed that upon switch blade 36 moving to the right, as occurs with a temperature rise, the switch blade 36 engages contact 39 before it leaves contact 38. Upon a temperature fall, or in other words, upon switch blade 36 moving to the left, the switch blade does not engage contact 38 until it has disengaged contact 39. Thus the switch assembly is overlapping on temperature rise but non-overlapping on temperature fall. Such an arrangement is shown in the patent to F. S. Denison et al., 1,941,540 of January 2, 1934. The switch blade 37 is overlapping on temperature rise, that is, upon moving to the right it engages contact 41 before it disengages contact 40. It is immaterial as to the sequence of contact engagement when the switch blade 37 is moving in the reverse direction. Ordinarily, because of the greater simplicity of such a construction, the switch blade 37 would be overlapping in both directions.

Power for the system is supplied by two line wires 43 and 44. These line wires lead to any suitable source of power (not shown).

Located adjacent to the oil burner nozzle 12 are two electrodes 50 and 51. These two electrodes are shown merely in schematic form in Figure 1, the electrode 50 being shown in more detail in Figure 2. As indicated in Figure 1, a step-up transformer 53 is employed for supplying high voltage power for the energization of the circuit including the electrodes 50 and 51. This transformer comprises a line voltage primary 54 and a high voltage secondary 55, to one terminal of which electrode 51 is connected by a conductor 66.

Referring now to Figure 2, the structure of the ignition electrode 50 is shown in greater detail. This electrode comprises an electrode tip 56 forming the electrode proper. This tip 56 is secured to a cylindrical shell 57 of insulating material of suitable heat resistant properties. Located within the insulating shell 57 is an inductance coil 58, whose coil is electrically connected by a conductor 68 at one end to the electrode tip 56 and by a conductor 69 at its other end to an insulated conductor 61 forming one of the leads of the ignition circuit. Surrounding the insulating shell 57 and electrically connected to conductors 68 and 61 is an elongated metal cup-shaped member 68. Surrounding member 63 is an insulating sleeve 64 and surrounding this sleeve is a second elongated metallic cup-shaped member 65. The two cup-shaped members 63

and 65 which are separated by the insulating sleeve 64 constitute a condenser indicated schematically in Figure 1 and represented there by the reference numeral 66. As previously stated, the inner member 63 is connected to conductors 60 and 61. The outer member 65 is connected by a conductor 67 to a resistance wire 69 having a relatively high temperature co-efficient of expansion. Wire 69 is in turn connected to conductor 59 leading to the electrode 56. The wire 69 is slidably supported in suitable supports 73 and 74 of insulating material and secured to the opposite ends of wire 69 is a member 70 of resilient material which by reason of the fact that it is of greater length than wire 69 is maintained in a bowed condition. Secured to the resilient member 70 is a contact 71 which is adapted to engage a fixed contact member shown only schematically in the drawing and indicated by the reference numeral 72.

As can be readily ascertained from the schematic showing of Figure 1, the assembly of the electrode unit 50 includes an inductance 58 and the condenser 66 connected in parallel, the condenser having the wire 69 in series therewith. Both the inductance and condenser, while connected in parallel with each other, are connected in series in the ignition circuit. The value of condenser 66 is so chosen with respect to inductance 58 that the condenser and inductance are in parallel resonance with each other at the high frequency of the current accompanying the discharge between electrodes 50 and 51. Due to the inherent distributed capacity in the ignition circuit, there is inevitably an oscillatory discharge across the spark gaps of relatively high frequency. It is this high frequency at which the condenser 66 and inductance 58 are resonant.

Operation of species of Figures 1 and 2

The various elements of the system are shown in the relative positions which they occupy when the temperature in the space heated by burner 10 is at or above the desired value. Let it be assumed now that the temperature begins to fall so that contact arm 17 of the thermostat 15 is moved into engagement with contact 18. When this occurs, the following circuit will be established to relay coil 20: from line wire 43, through conductor 75, bimetallic element 16, contact arm 17, contact 18, conductor 76, switch blades 28 and 29, conductor 77, switch blade 36, contact 38, conductor 78, heating element 31, conductor 79, relay coil 20, and conductor 80 to the other line wire 44. The establishment of this circuit causes the energization of relay coil 20 with the result that switch blades 22 and 23 are moved into engagement with contacts 24 and 25.

The movement of switch blade 23 into engagement with contact 25 results in the establishment of the following circuit to the primary 54 of the ignition transformer 53: from line wire 43 through conductor 81, contact 25, switch blade 23, conductor 82, switch blade 37, contact 40, conductor 83, primary winding 54, and conductor 84 to the other line wire 44. The energization of primary 54 results in the energization of the ignition circuit so that normally a spark is produced between electrodes 50 and 51. If a proper spark occurs, the current will consist primarily of two components, one a low frequency component, the frequency of which is the same as the frequency of the supply source. The other component will be a high frequency one, the frequency of which is determined by the constants of the circuit.

The great majority of the low frequency current flow through the portion of the circuit including the inductance 58. The high frequency current which enters the loop including the condenser 66 and inductance 58 will assume a relatively large value within said loop due to the fact that the loop constitutes in effect a series resonant circuit for the current of that frequency and thus provides an impedance which, except for the resistance 69, is relatively negligible. The high frequency current by reason of its relatively large value will cause wire 69 to become heated. This in turn will cause the wire to expand permitting the bowed member 70 to move towards a more straightened position. This movement of member 70 brings the contact 71 into engagement with the fixed contact 72. Upon this happening, the following circuit is established to the oil burner motor 11: from line wire 43 through conductor 20 25 contact 25, switch blade 23, conductor 87, contacts 12 and 71, conductors 88 and 89, burner motor 11, and conductor 90 to the other line wire 44. The establishment of this burner motor circuit results in fuel being ejected through the nozzle 12, which fuel by reason of the existence of a proper spark between the electrodes 50 and 51 is immediately ignited.

The ignition of the burner will result almost immediately in a rise in the stack temperature causing the switch blades 36 and 37 to be moved to the right. The movement of switch blade 36 to the right causes first the engagement thereof with contact 39 and then the disengagement thereof from contact 38. Upon the switch blade 36 engaging the contact 39, the following holding circuit is established to the relay 20: from line wire 43 through conductor 75, bimetallic element 16, contact arm 17, contact 18, conductor 76, switch blades 28 and 29, conductor 77, switch blade 36, contact 38, conductor 81, switch blade 22, contact 24, conductor 82, relay coil 20 and conductor 80 to the other line wire 44. It will be noted that this new circuit is independent of the heating element 31. The disengagement of switch blade 36 from contact 38 causes the interruption of the previously traced circuit to the heating element 31. By reason of the overlapping action, the new circuit is established before the interruption of the old circuit so that there is no interruption in burner operation. The interruption of the circuit to heating element 31 causes this element to no longer be raised in temperature so that it is assured that the burner motor will remain in operation.

55 The movement of switch blade 37 into engagement with contact 41 results in the establishment of the following new circuit to oil burner motor 11: from line wire 43 through conductor 81, contact 25, switch blade 23, conductor 82, switch blade 37, contact 41, conductors 83 and 88, burner motor 11, and conductor 86 to the other line wire 44. It will be noted that this new circuit is independent of contacts 71 and 72. The disengagement of switch blade 37 from contact 40 results in the interruption of the previously traced ignition circuit. The ignition is thus deenergized, being no longer needed since the oil burner is now in operation. If it were not for the establishment of the last traced oil burner circuit, separation of contacts 71 and 72 by reason of the deenergization of the ignition apparatus would stop the oil burner. By reason, however, of the new circuit which in effect parallels the contacts 71 and 72, the oil burner motor continues in operation.

The operation which has just been described is that which occurs when combustion takes place in the ordinary manner. If the oil burner is never started by reason of a proper spark not being established or if for some other reason combustion is not established, the circuit to heating element 31 will not be interrupted. The result is that after a predetermined period of time, the bimetallic element 30 is warped sufficiently to the right to permit separation of switch blades 28 and 29. Such separation will interrupt all of the circuits to relay coil 20 and completely deenergize the system. The system will not again be placed into operation until the switch blades 28 and 29 are again reclosed manually. This necessity for a manual resetting of the switch blades 28 and 29 insures that the operator will have a chance to determine the cause of the failure of combustion.

If at any time after combustion has been established it is interrupted for some reason or other, the stack temperature will again cool causing stack switch blades 36 and 37 to be moved to the left. The movement of switch blade 36 out of engagement with switch blade 39 causes the deenergization of the holding circuit for relay coil 20. Since the switch blade 36 does not engage contact 38 until some time after it is separated from contact 39, there will be a period during which there is no energizing circuit for relay coil 20. During this period, the oil burner is out of operation permitting any accumulation of vaporized oil which may be present to escape up the stack. On switch blade 36 reengaging the contact 38, relay coil 20 will again be reenergized by reason of the establishment of the first traced energizing circuit therefor. The movement of switch blade 37 to the left into engagement with contact 40 again reestablishes, upon energization of relay coil 20, the circuit through the ignition transformer primary 54. The separation of switch blade 37 from contact 41 assures that the oil burner cannot be reestablished until contacts 71 and 72 are again closed by the proper operation of the ignition apparatus. As soon as these contacts are closed, the oil burner is placed in operation and the remainder of the cycle is the same as that previously traced.

It will thus be seen that both in starting and upon recycling after flame failure, the present arrangement offers a relatively simple method of insuring that the oil burner is not placed in operation until there is a proper spark. It will further be noted that the apparatus will not falsely respond to a spark occurring somewhere between the ignition leads. This is a very serious problem inasmuch as the ignition circuits are usually of quite high voltage. In spite of efforts to insulate the conductors between the ignition transformer and the spark electrodes, breakdown often does occur. In certain prior arrangements, it has been proposed to employ various devices, some responsive to high frequency potentials, which are solely responsive to the potential existing across the two leads. The disadvantage of such devices is that they respond in case of any breakdown between the ignition leads due to the fact that in spite of the breakdown a high frequency voltage exists between these leads even though there be no spark in the spark gap whatsoever. The present arrangement by reason of the fact that it is connected closely adjacent the ignition electrode and in series therewith prevents any such false indication of

a proper spark by reason of a spark between the ignition leads.

Species of Figures 3 and 4

5 In Figures 3 and 4, a slightly different form of the invention is shown. Inasmuch as the oil burner circuit is substantially the same as in the species of Figures 1 and 2, only a portion of the oil burner circuit has been shown. In view of the 10 fact that the oil burner is identical, it has been given the same reference characters as in Figure 1, the oil burner motor being designated by the reference numeral 11 and the nozzle by the numeral 12. The ignition electrodes in this species 15 are designated by the reference numerals 101 and 102, respectively. The electrode 102, like the electrode 50 of the previously described species, consists of an assembly of several elements. The electrode 102 comprises an electrode tip 103 constituting the electrode proper. This tip 103 is secured to a shell 104 of insulating material of suitable heat resistant properties. Located within the insulating shell 104 is an inductance coil 105 which has a central passage therethrough. The 20 inductance coil 105 is so designed that its distributed capacity makes the coil 105 resonant at frequencies accompanying a proper spark in the ignition circuit. One end of the inductance coil 105 is connected by a conductor 106 to the electrode tip 103. Located within the passage of coil 105 is a bulb 107 which is connected to a metallic tube 108. Tube 108 is connected at its outer 25 extremity to a bellows 109 which bears against a pivoted support member 110 for a mercury switch 111. The mercury switch 111 is of conventional structure comprising a pair of contacts 113 and 114 which are adapted to be bridged by a mercury element 115. A spring 112 biases the support 110 to a position wherein the mercury 30 element 115 is out of engagement with contacts 113 and 114. The left-hand end of the coil 105 is connected by a conductor 116 to the metal tube 108, which in turn is connected to a conductor 117 which leads to one terminal of the ignition 35 transformer.

The bulb 107 is of relatively high conductivity so as to form a short circuited secondary for the inductance coil 105. It will be readily seen that when a high frequency current flows through the 40 inductance 105, the currents introduced in the metallic bulb member 107 will be of sufficiently great intensity as to heat the bulb 107. Due to the resonant nature of the coil 105, these currents will flow only when a proper spark occurs 45 between the electrodes. Located within the bulb 107 is a mixture 120 consisting of gas and activated charcoal. Under normal conditions, the gas will largely be absorbed by the activated charcoal. As the temperature of the bulb 107 50 rises, however, gas will be forced out of the activated charcoal expanding the bellows 109 and causing the mercury switch 111 to be tilted to its closed position wherein contacts 113 and 114 are bridged by mercury switch 115. It is to be understood that in lieu of the gas and activated 55 charcoal fill, there may be substituted a fill of a suitable volatile fluid which is adapted to operate within the temperature range to which it will be subjected by heating of bulb 107.

70 It is believed that the operation of this species will be apparent. Whenever a proper spark exists, bulb 107 is heated up to expand bellows 109 and close mercury switch 111. As indicated in Figure 3, the contacts 113 and 114 of the mercury switch 111 are connected in the same manner as

the contacts 71 and 72 of the previously described species. These contacts perform the same function as contacts 71 and 72 of the other species.

It will be seen that in both modifications of my invention a very reliable checking of the spark 5 is obtained with a relatively simple structure which occupies very little additional space, while in both species, the various disadvantages outlined for the prior art are successfully avoided without any accompanying disadvantages of their 10 own.

While certain specific embodiments of the invention have been shown, it is to be understood that these are for purposes of illustration only and that the invention is to be limited only by 15 the scope of the appended claims.

I claim as my invention:

1. In combination, a burner, means controlling the flow of fuel to said burner, an ignition circuit including a pair of spaced electrodes for igniting the fuel supplied by said fuel flow controlling means, one of said electrodes having a hollow portion, temperature responsive means within said hollow portion, means associated with said electrode to heat said temperature responsive 20 means upon the occurrence of a proper spark between said electrodes, a control device actuated by said temperature responsive means, and means including said control device operative to so control the fuel flow controlling means as to cause a 25 flow of fuel to said burner only when there is a proper spark between said electrodes.

2. In combination, a burner, means controlling the flow of fuel to said burner, an ignition circuit including a pair of spaced electrodes for igniting 30 the fuel supplied by said fuel flow controlling means, one of said electrodes having a hollow portion, a fluid filled member within said hollow portion, means associated with said electrode to heat said member upon the occurrence of a proper 35 spark between said electrodes, a control device, fluid pressure actuated means connected to said fluid filled member and operatively connected to said control device to move the same to either of two controlling positions, and means including 40 said control device operative to so control the fuel flow controlling means as to cause a flow of fuel to said burner only when there is a proper spark between said electrodes.

3. In combination, a burner, electrically operated means controlling the flow of fuel to said burner, an ignition circuit including a pair of spaced electrodes for igniting the fuel supplied by said fuel flow controlling means, one of said electrodes having a hollow portion, temperature 50 responsive means in said hollow portion, means associated with said electrode to heat said temperature responsive means upon the occurrence of a proper spark between said electrodes, a switch 55 associated with said electrode and operatively connected to said temperature responsive means to be actuated thereby, and means including said temperature responsive means and said switch operative to so control the fuel flow controlling means as to cause a flow of fuel to said burner 60 only when there is a proper spark between said electrodes.

4. In combination, a burner, electrically operated means controlling the flow of fuel to said burner, an ignition circuit including a pair of 70 spaced electrodes for igniting the fuel supplied by said fuel flow controlling means, one of said electrodes having a hollow portion, a fluid filled member in said hollow portion, means associated with said electrode to heat said temperature re-

- sponsive means upon the occurrence of a proper spark between said electrodes, a switch, fluid pressure responsive means connected to said fluid fuel member and operatively connected to said switch 5 for actuating the same, and means including said switch operative to so control the fluid fuel controlling means as to cause a flow of fuel to said burner only when there is a proper spark between said electrodes.
- 0 5. In combination, a burner, electrically operated means controlling the flow of fuel to said burner, an ignition circuit including a pair of spaced electrodes for igniting the fuel supplied by said fuel flow controlling means and having sufficient capacity that the occurrence of a proper 10 spark between said electrodes causes the flow of a high frequency current in said ignition circuit, one of said electrodes having a hollow portion including inductance and capacitive means connected in parallel with each other and in series with the remainder of the electrode and a switch actuating means associated with said inductance and capacitive means, a switch associated with said electrode and operatively associated with said 15 switch actuating means, and means including said switch operative to so control the fuel flow controlling means as to cause a flow of fuel to said burner only when there is a high frequency current flow in said ignition circuit.
- 10 6. In combination, a burner, electrically operated means controlling the flow of fuel to said burner, an ignition circuit including a pair of spaced electrodes for igniting the fuel supplied by said fuel flow controlling means and having sufficient capacity that the occurrence of a proper spark 20 between said electrodes causes the flow of a high frequency current in said ignition circuit, one of said electrodes having a hollow portion including inductance and capacitive means connected in parallel with each other and in series with the remainder of the electrode, a switch actuating means including a heating device located in said electrode and connected in series with said capacitive means, a switch associated with said electrode and operatively associated with said switch actuating means, and means including said switch 25 operative to so control the fuel flow controlling means as to cause a flow of fuel to said burner only when there is a high frequency current flow in said ignition circuit.
7. In combination, a burner, electrically operated means controlling the flow of fuel to said burner, an ignition circuit including a pair of spaced electrodes for igniting the fuel supplied by said fuel flow controlling means and having sufficient capacity that the occurrence of a proper spark 30 between said electrodes causes the flow of a high frequency current in said ignition circuit, one of said electrodes having a hollow portion including inductance and capacitive means connected in parallel with each other and in series with the remainder of the electrode, a switch associated with said electrode, fluid pressure responsive means for actuating said switch, a fluid filled metallic receptacle connected to said pressure responsive means and located in inductive relationship with said inductance whereby upon the flow of high frequency current in said inductance said metallic receptacle is heated by reason of the current flow induced therein, and means including said switch operative to so control the fuel flow controlling means as to cause a flow of fuel to said burner only when said receptacle 35 is heated.
8. In combination, a burner, electrically operated means controlling the flow of fuel to said burner, an ignition circuit including a pair of spaced electrodes for igniting the fuel supplied by said fuel flow controlling means and having sufficient capacity that the occurrence of a proper spark 40 between said electrodes causes the flow of a high frequency current in said ignition circuit, one of said electrodes having a hollow portion, an inductance element in said hollow portion, a metallic shell surrounding said inductance element, a second metallic shell surrounding said previously named shell and insulated therefrom, said shells collectively acting as a condenser and as a casing for said hollow portion, a switch actuating means associated with said inductance element and said condenser, a switch associated with said electrode and operatively associated with said switch actuating means, and means including said switch operative to so control the fuel flow controlling means as to cause a flow of fuel to said burner only when there is a high frequency current flow in said ignition circuit.

MEADE J. MAYNARD.
